UNITED STATES PATENT OFFICE

151,633

DESIGN FOR A THERMOMETER CASING AND MINUTE GLASS UNIT

Michael Graboi, New York, N. Y.

Application October 8, 1947, Serial No. 141,805

Term of patent 3½ years

(Cl. D83—1)

To all whom it may concern:

Be it known that I, Michael Graboi, a citizen of no country, and resident of New York, in the county of New York and State of New York, have invented a new, original, and ornamental Design for a Thermometer Casing and Minute Glass Unit of which the following is a specification, reference being had to the accompanying drawing, forming a part thereof, and in which Figure 1 is a perspective view of a thermometer casing and minute glass unit showing my new design; and Fig. 2 is a top plan view thereof.

The opposite sides of the thermometer casing and minute glass unit are identical.

I claim:

The ornamental design for a thermometer

casing and minute glass unit, substantially as shown and described.

MICHAEL GRABOI.
